UNITED STATES PATENT OFFICE.

JOHN H. EVANS, OF BRIDGEPORT, PENNSYLVANIA.

TOY.

1,299,696.

Specification of Letters Patent.

Patented Apr. 8, 1919.

Application filed September 1, 1917. Serial No. 189,252.

To all whom it may concern:

Be it known that I, JOHN HOWARD EVANS, a citizen of the United States, residing at Bridgeport, in the county of Montgomery and State of Pennsylvania, have invented certain new and useful Improvements in Toys, of which the following is specification.

My invention relates to improvements in 10 toys, and more particularly to an improved wheeled toy, the body of which represents a boat supported on wheels and caused to move by means of an improved arrangement of toggle levers and oars.

15 A further object, is to provide an improved mounting for a caster wheel at the front end of the body, which allows the body to be guided by the movement of the oars.

20 A further object is to provide a toy of the character described which can be manufactured and sold at a reasonably low price, which will be neat and attractive in appearance, and which will be strong and durable in use.

25 With these and other objects in view the invention consists in certain novel features of construction and combinations and arrangements of parts as will be more fully hereinafter described and pointed out in the 30 claims.

In the accompanying drawings:

Figure 1 is a top plan view, illustrating my improvements.

Fig. 2 is a view in side elevation and

35 Fig. 3 is a view in section on the line 3—3 of Fig. 2.

1 represents the body of my improved toy, which is preferably in the form of a boat, having a sliding seat 2, supported in 40 any approved manner in the body.

The rear end of body 1, is supported by two driving wheels 3—3, which are mounted on an axle 4.

45 The front end of the body is supported by a caster wheel 5, mounted in a vertical fork 6, supported to turn in a vertical bearing sleeve 7, on body 1. A practically horizontal fork 8, straddles caster wheel 5, and is connected to fork 6. This fork 8 is con-

50 nected to the body 1, by means of a coiled spring 9, which normally holds the caster wheel in straight or longitudinal position, but allows it to pivot or castor as occasion may require but always returns the wheel to 55 its normal straight position.

The driving mechanisms on both sides of

body 1, are precisely alike and hence the description of one will apply alike to both. Each driving mechanism employs a vertically positioned toggle lever 10, consisting 60 of four links 11, 12, 13 and 14. A vertical lever 15 is pivotally supported between its ends on a pin 16 forming a part of a bracket 17, rigidly secured to body 1. This pin 16 is connected to the upper and lower ends of the toggle lever 10 by means of links 18 and 19, which maintain the toggle lever in a vertical position. The lever 15, above and below its pivot 16 is connected by links 20 and 21 respectively with the opposite sides 70 or intermediate pivots 22 and 23 of the toggle lever 10. A pitman 24 connects pin 23 with a crank pin 25 on the driving wheel 3, so that the movement of the toggle is transmitted to the wheel. 75

The driving mechanisms on the sides of the body 1, are operated by two oars 26, pivotally supported near their outer ends as shown at 27 and having slots 28 in their outer ends which receive the upper ends of 80 levers 15.

The operation of the toggle levers is as follows:

85 The pivots 16, 22 and 23 are maintained in horizontal alignment by means of the links 18 and 19. The movement of lever 15 through the medium of links 20 and 21 causes the toggle lever to expand and contract, and hence impart a steady movement to pitman 24, to rotate driving wheel 3 and 90 propel the toy.

95 The operation is very much the same as that of rowing a boat, and the movement of the toy can be guided or steered by causing one oar to move more than the other in accordance with the direction it is desired to take.

100 Various slight changes may be made in the general form and arrangement of parts described without departing from my invention and hence I do not limit myself to the precise details set forth, but consider myself at liberty to make such changes and alterations as fairly fall within the spirit and scope of the appended claims. 105

Having fully described my invention, what I claim as new and desire to secure by Letters Patent is:

110 1. A toy of the character described, comprising a body and driving wheels supported by the body, a toggle lever carried by the body, rigid connections from opposite ex-

- tremities of the lever to a relatively fixed point on the body, a single operating lever and connections, one from the operating lever and one from one of the wheels to a common intermediate point on the toggle lever. 5
2. A toy of the character described, comprising a body, driving wheels on the body, a toggle lever construction carried by the body, rigid connections from opposite extremities of the toggle lever to a relatively fixed point on the body, a single operating lever and connections from the operating lever and from one of the wheels to a common intermediate point on the toggle lever 10 construction, and a second connection from the single lever to a different intermediate point upon the toggle lever construction.
3. A toy of the character described, comprising a body, and driving wheels supporting the body, toggle levers supported by the body, pitmen connecting the toggle levers with the driving wheels, levers pivotally supported by the body, links connecting the last mentioned levers with the toggle levers, 15 and oars operating the first mentioned levers. 20
4. A toy of the character described, comprising a body, driving wheels supporting the body, and having crank pins thereon, levers pivotally supported between their ends 25

by the body, toggle levers, links connecting the upper and lower ends of the toggle levers with the pivots of the first mentioned levers, links connecting the intermediate pivots of the toggle levers with the first mentioned levers above and below the pivots of the latter, and pitmen connecting the toggle levers with the crank pins on the driving wheels. 30

5. A toy of the character described, comprising a body, two driving wheels supporting the rear end of the body and having crank pins thereon, a caster wheel supporting the front end of the body, a fork connected to the caster wheel support, a spring connecting the fork with the body and normally holding the caster wheel in a straight line longitudinal of the body, levers on the sides of the body operatively connected to the crank pins on the driving wheels, and oars pivotally connected to the body and 35 operatively connected to said levers. 40

In testimony whereof I have signed my name to this specification in the presence of two subscribing witnesses.

JOHN H. EVANS.
